ACOUSTIC WALL BOARD

Kichiro Izumiya, Shibuya-Machi, Toyotama-Gun, Tokyo-Fu, Japan

Application February 24, 1932, Serial No. 594,838

1 Claim. (Cl. 154—44)

This invention relates to improvements in wall boards for acoustic purposes and for insulating purposes, and more particularly in acoustic wall boards of the type manufactured from ground 5 pulp, sliced bagasse or generally crushed vegetable fibrous materials.

The main object of this invention is to provide an improved wall board of maximum efficiency in absorbing sound for acoustic purposes and also 10 of maximum efficiency for insulating purposes.

Wall boards for acoustic and insulating purposes hitherto in use, such as "celotex", "acousticcelotex", "insulite", etc., are uniform in density throughout their entire extent and generally 15 present flat surfaces. Therefore sound waves which fall on and enter such boards pass directly therethrough and are but slightly absorbed. They are also of but slight efficiency as insulators.

According to this invention, however, the density 20 of the board is not uniform and the board is so constructed that the parts of minimum density are embossed lattice wise, checkered or in other suitable form so as to cause the sound waves which fall on the board to proceed from comparatively dense parts to less dense parts thereof, and to be thereby absorbed to maximum extent. Moreover, as the board constructed according to 25 this invention is laid on the wall in such manner that the embossed parts come in contact with the wall, non-communicating spaces are formed 30 between the board and the wall, which are filled with confined air, and are very effective for absorbing sound and for insulating purposes.

The accompanying drawing is a perspective of 35 a portion of a wall board constructed in accordance with my invention.

In the drawing 1 represents a coarse part of

the board of minimum density and embossed lattice wise and 2 represents a compact part of the board of maximum density.

As the board is laid and secured on a wall, for example, by screws, the embossed coarse parts 60 1 being brought in contact with the wall, sound waves which fall on the board are caused to pass therethrough from comparatively compact parts of maximum density to coarse parts of minimum density and are hence refracted and absorbed. 65

It will be noted that the recesses are isolated from one another, that the density of the local areas corresponding to the recesses is greater than that of the local areas corresponding to the intermediate portions, and that, when the board is 70 secured on a wall, with its embossed side presented thereto and in contact therewith, air is confined in the non-communicating recesses and the board is of maximum efficiency as an insulator.

Although the features of the invention are as 75 illustrated and described, it is to be understood that changes in the details of construction may be made within the scope of the invention as claimed.

What is claimed is,

An insulating and sound absorbing wall board 80 of fibrous material embossed on one side and thereby provided with non-communicating recesses and intermediate portions of the full thickness of the board, the density of the board in 85 the local areas corresponding to the recesses being greater than that of the local areas corresponding to the intermediate portions, said recesses being bounded by said intermediate portions so that said intermediate portions form the sides of the 90 recesses and isolate said recesses.
